UNITED STATES PATENT OFFICE.

WILLARD G. THORPE, OF LOS ANGELES, CALIFORNIA.

BURGLAR DETECTOR.

Application filed December 27, 1926. Serial No. 157,331.

An object of this invention is to provide a cheap, compact, simple, effective device for application to doors and windows or other available supports where the same is likely to be disturbed by an intruder, and which device is for the purpose of producing a noise that will cause the intruder, such as a burglar, to take alarm, and which will also give such a signal as can be heard for a considerable distance so as to arouse occupants of the house or people in the neighborhood; thus reducing the liability of robbery, depredation or murder.

Another object is to make provision whereby a moderate amount of explosion will produce a considerable detonation, thus to minimize the danger likely to be attendant on using explosives for this purpose, and to make the device practically harmless.

The invention is broadly new, basic and pioneer in that it comprises spring actuated jaws adapted to form between them, when closed, an explosion chamber having an expanding opening at one side and preferably having such opening in the form of three or more radial bores each of which is expanded by steps outwardly and is shaped so as to magnify the sound produced inside the chamber by the detonation of a paper cap exploded by means contained inside the chamber and adapted to hold the paper cap without danger of explosion until the jaws are opened and suddenly released so that the spring may forcibly bring them together.

By this arrangement the detector is adapted to be carried in hand bags or in the vest pocket without being in the way, or being likely to cause damage.

A feature of the invention is that the explosion chamber and the bores are divided and are adapted to be opened when the jaws are separated thus to allow the paper cap to be placed in position to be exploded; and this allows one to clean out the chamber and bores.

Another object is to make provision for ready application to the door and door casing, window and window casing, or to another support.

An object is to make provision whereby the detector may be left in place at all times ready to be set as occasion may require and whereby it may be instantly detached for removal from the room.

This invention is intended to so construct a detonator that it will give in combination

a sharp report like that of a rifle and also a loud roar or voluminous report like that of a shot gun, and to increase the volume of the report by a peculiar stepped and sectional construction of counterbores.

I make provision whereby the detonator barrel is formed in halves; the cap being located in a breech chamber and split lengthwise of the bores or barrels, and I make provision whereby the breech chamber can be located at one side of the anvil and firing head which are pivoted eccentrically and the bores lead from such chamber to the other edge of the detonator, thereby increasing the length of the bores; the placing of the paper cap for detonation being the same.

The invention includes the novel detonator and the various novel features thereof set forth.

An object is insuring that the paper cap will remain in place until detonated.

Another object is to adapt the detonator to be applied to the casing or other support in various positions and this I accomplish by arranging a plurality of differently positioned pairs of key-hole slots in the attaching limb of the detonator to catch upon studs provided in various positions on the support or supports, as door or window casings, floors or baseboards etc. as may prove most convenient or desirable.

Other objects, advantages and features of invention may appear from the accompanying drawing, the subjoined detailed description and the appended claims.

The invention may be applied in various forms.

The accompanying drawing illustrates the invention in the form at present deemed most desirable.

Figure 1 is a perspective view of the invention applied to a door casing and door, fragments of which are shown, and set ready to serve as a detector of any opening of the door.

Fig. 2 is an edge view of the detector as set; the casing and door being in horizontal section; dotted lines indicate a position of the firing head at the moment the device is about to be set off by the opening of the door.

Fig. 3 is a longitudinal section on line x^3 , Fig. 4, showing the device on a somewhat larger scale, and detached; a paper cap is shown in place.

Fig. 4 is an enlarged view of the anvil

and its holder omitting the firing head and showing the spring in section on line x^4-x^5 , being taken at x^4-x^5 , Figs. 2 and 3, and also showing a paper cap in place on the anvil.

5 Fig. 5 is a fragmental view of the firing head looking in the opposite direction to Fig. 4.

Fig. 6 is an end elevation of the device looking from the right of Fig. 1.

10 Fig. 7 is a view analogous to Fig. 5 showing an eccentric form of firing head.

In the form shown, the invention comprises a double limbed body of spring steel consisting of a straight stationary hub 1 and 15 a striking limb 2; the stationary or attaching limb 1 is adapted to be fastened to a stationary support as a window casing or a door casing 3, and the movable striking limb 2 is provided with a tip 4 that extends a 20 short distance beyond the end of the stationary limb 1 and into the path of a lug 5 on a movable part or support as the door 6 of a building.

The ends of the stationary limb 1 and 25 movable limb 2 are provided respectively with an anvil 7 and a striker or firing head 8 which form a split and combined breech piece and barrel and said anvil and head are complementary to, and cooperate with 30 each other to detonate a paper cap 9 when the same is placed on the anvil, and in the burglar detecting action the limb 2 with its head is moved from the limb 1 and the paper cap 9 on the anvil 7 by the opening of the 35 door 6, and is released as the door further opens, thus escaping the tip 4, and leaving the striker or firing head 8 free to be spring driven back onto the cap 9 on the anvil, thus to cause the explosion of the cap in a recess 40 provided in said anvil. The firing head 8 is provided with a projecting striking face, boss or knob 11 to detonate the cap, and such knob is provided with a recess 12 into which the gases from the detonation 45 may expand and said anvil and head have outwardly expanding and outwardly opening complementary stepped cavities 13, 14 to communicate with the cavity in the anvil, the recess in the striking head and the open 50 air at one side of the anvil and head.

The stepped cavities are complementary to each other so as to form radial bores through which the detonation may expand outwardly into the surrounding air, and thus producing an amplified sound, increasing the noise made by the explosion.

The anvil 7 and the striking head or hammer 8 are rotatably secured to their respective spring limbs 1 and 2 by means of studs 60 15 inserted through holes 16 in said limbs and riveted tightly in place to frictionally hold the anvil and the head in predetermined position, but allowing such parts to be simultaneously rotated on their limbs to 65 direct the bores formed by the recesses 13

and 14, with respect to the spring limbs, thus to accommodate the convenience of any particular situation.

The attaching limb 1 is shown provided with key-hole slots arranged in pairs as at 70 17 and 18 to receive the supporting studs 19 that are shown as round screws 19 that are screwed into the stationary part 3 of the building.

The anvil is provided with a semi-circular guard 20, to extend across the crack 21 between the anvil and striking head when they explode the cap to prevent out-flash of fire around the anvil and head except at the side at which the bores open. 75

The stationary limb 1 is flat so as to fit snugly against the stationary part 3 when the device is fastened in place.

The bow 22 of the appliance is arcuate, 80 extending beyond the plane of the striking limb 2 so that when said striking limb is drawn out and allowed to spring back into place, the striking head will escape the guard 20 and come into position without interference, and with said guard across said 90 crack 21.

It is understood that in case the striking head is arranged as at 8', Fig. 7, with its boss 11' eccentrically located the anvil not shown will be conformed thereto so that the 95 cap will be exploded as in the other form.

What I claim as new and novel:—

1. A detonator having sound amplifying barrels and split its entire length from breech to the muzzles. 100

2. A detonator having an anvil and a firing head provided with complementary diverging bores leading to the outside.

3. A detonator barrel having a stepped expanding bore for stepping up the sound 105 and increasing the volume thereof.

4. A burglar detector comprising a U-spring, an anvil and a hammer, two bodies fixed to the spring members at equal distances from the bend and respectively provided with outwardly widening radial bores, one of said bodies being provided with a chamber adapted to accommodate a flat fulminate cap and the other provided with a boss adapted to enter the cavity and strike 110 the bottom thereof or a sheet-like fulminate cap on such bottom; said bores radiating from said cavity for the purpose of directing the force of the explosion toward the edge of the two members and to increase the 115 sound of the explosion.

5. A burglar detector comprising a U-spring, an anvil and a hammer, two bodies fixed to the spring members at equal distances from the bend and respectively provided with outwardly widening radial semi-bores, one of said bodies being provided with a chamber adapted to accommodate a flat fulminate cap and the other provided with a boss adapted to enter the cavity and 120 125 130

strike the bottom thereof, or a sheet-like fulminate cap on such bottom; said bores radiating from said cavity for the purpose of directing the force of the explosion toward the edge of the two members and to increase the sound of the explosion, the floor of the cavity being flat and the end of the striker being concave so as to form an annular space around the center of the concavity, 10 said space communicating with the smaller ends of the outward stepped composite bores.

6. A burglar detector comprising a U-shaped spring, a body connected to one of the spring members and having a face mainly flat and provided with outwardly expanding stepped semi-bores and with a central cavity with which the inner smaller ends of the bores communicate; a body connected to the other of the spring members, and provided with a central boss adapted to enter the cavity of the first body when the

spring is free to close, the face of said second mentioned body being mainly flat and adapted to fit tightly upon the face of the first mentioned body and provided with outwardly expanded stepped semi-bores to operate in conjunction with the semi-bores of said first mentioned body.

7. A detonator comprising an anvil and striking head connected by spring means and arranged to be operated against the force of the spring means; and unitedly forming a breech, a firing chamber and barrel having a muzzle at one side of the breech; and a guard to cover that portion of the crack between the anvil and head on the other side of the breech to prevent out-flash of fire on that side of the breech.

In testimony whereof, I have hereunto set my hand at Los Angeles, California, this 16th day of December, 1926.

WILLARD G. THORPE.
